RALPH R. LAPOINTE, OF HUDSON, MASSACHUSETTS, ASSIGNOR TO LAPOINTE MACHINE TOOL CO., OF HUDSON, MASSACHUSETTS, A CORPORATION OF MAINE.

SPIRAL-BROACHING MECHANISM.

1,177,527.

Specification of Letters Patent. Patented Mar. 28, 1916.

Application filed May 16, 1912. Serial No. 697,740.

To all whom it may concern:

Be it known that I, RALPH R. LAPOINTE, a citizen of the United States, and resident of Hudson, county of Middlesex, State of Massachusetts, have invented an Improvement in Spiral-Broaching Mechanisms, of which the following description, in connection with the accompanying drawings, is a specification, like letters on the drawings representing like parts.

The present invention relates to mechanism for broaching spiral channels or grooves in the walls of the center passages through hollow work-pieces, and in its preferred embodiment is constructed as an appliance adapted for attachment and assemblage with a standard type of broaching machine.

In the illustrative form of the invention herein shown, my improvements are applied to the well known Lapointe broaching machine of the draw-cut type.

The invention will be better understood from the following detailed description, taken in connection with the accompanying drawings, and will be thereafter pointed out in the appended claims.

Referring to the drawings, Figure 1 is a side elevation showing my improvements applied to the head of a broaching machine, a fragmentary portion of such head and the operating draw-screw of the machine being shown broken away; and Fig. 2 is a view partly in elevation and partly in central vertical section, showing essential parts of the improved mechanism, other parts being omitted and broken away.

The head or thrust face of the broaching machine is indicated at 10, and the operating draw-screw at 11, extending into engagement with a cross-head slide 12, suitably guided in ways from the machine frame. The broach 13, which is shown as of known form provided with a spiral rib 14 gradually rising from the body of the broach and interrupted at intervals to form cutting teeth, is secured to the cross-head slide 12 by a key fastening 15, or other suitable means adapted to impart reciprocation thereto from the operating draw-screw and hold it rigidly against turning on its axis.

My invention provides means whereby a hollow work-piece fitted on the broach is given a controlled rotating movement simul-

taneously with the reciprocating movement of the broach in exactly the proper timed relation to correspond with the spiral incline or pitch of the cutting rib on the broach, so that such rib will produce a spiral channel or groove or like incline in the work-piece. To this end a bracket yoke member 16, fixed to the thrust face 10 by flange and bolt clamping means 17, is provided with a bearing sleeve 18, within which is fitted a collar 19 having a flange 20 at one end provided with spiral gear teeth 21 and threaded at its other end, as seen at 22, to receive a bearing or holding ring 23, this ring and the flange 20 serving to hold the collar 19 against displacement relative to the sleeve 18. The collar 19 is shown as having fitted therein a hollow guide member 24 for the broach, this member being provided with a spiral groove or channel 25 of an incline or pitch corresponding to that of the rib 14 on the broach and of a suitable depth to receive the maximum height of said rib.

A work-piece *a* is shown in place on the broach fitting up against the hollow guide member 24, which is shown as flanged at 26 to resist thrusts thereon and the work-piece is held against rotation relative to the collar 19 and for controlled turning movement therewith by a clamp ring 27, having a projecting portion 28 engaging with a lug 29 on the end of the collar 19. To impart the requisite definite rotary movement to the collar 19, I mount a spiral gear 30 fixed on a shaft 31 to mesh with the spiral gear 21, in bearings on a bracket 32 extending up from the bearing sleeve 18, and on the shaft 31 a spur gear 33 is also fixed and arranged to mesh with a rack 34 formed on the under surface of a bar 35, rigidly mounted on a post 36 upstanding from and rigid with the cross-head slide 12, this rack being usually held in mesh by a guiding member (not shown). Thus, as the cross-head reciprocates, the rack 34 will operate the gear 33, and thence through the spiral gear connection 30, 21 effect turning of the collar 19, and hence effect or permit turning of the work-piece *a*.

It will be understood that the described gear connections are so proportioned that the reciprocatory movement of the rack 34, as imparted from the operating screw is transmitted at exactly the proper ratio to

effect the turning of the collar 19 at a rate relative to the rate of reciprocatory movement of the broach, so that a given point on the broach will travel relative to the 5 collar, and hence to the work-piece, in a direction to describe the same spiral incline or pitch as that of the spiral rib on the broach. Thus such spiral rib will produce a spiral channel or groove in the work-piece 10 of an incline or pitch the same as its own, in an expeditious and effective manner, and with a minimum of unnecessary friction or lost power. With the gearing connections correctly proportioned as described, it is 15 further possible to produce a channel or groove of accurate dimensions and clean cut of a size and depth as determined by the dimensions of the cutting rib by which it is produced.

20 I am aware that variations in details of construction may be resorted to without departing from the spirit of the invention, and I therefore do not desire to be limited as to these or in any other way, except as 25 set forth in the appended claims.

Having described my invention, what I claim as new, and desire to secure by Letters Patent is:

1. Apparatus of the kind described, comprising a broaching machine head, a broach 30 having a cutting projection formed and adapted for operation on reciprocation of the broach, means for applying power to the apparatus for reciprocating the broach 35 while holding it against rotation, and means for rotating a work piece mounted on said broaching machine head in timed relation to the reciprocation of the broach for producing a spirally broached cut.

40 2. Apparatus of the kind described, comprising a broaching machine head, a broach having a cutting rib formed as a relatively open spiral, means for applying power to the apparatus for reciprocating the broach 45 while holding it against rotation, a work

piece mounted for rotation on a face of said broaching machine head, and means actuated by said broach reciprocating means for controlling the rotation of said work piece in conformity with the pitch of said spiral 50 rib on the broach.

3. Apparatus of the kind described, comprising a broaching machine head, a broach provided with spirally arranged cutting elements adapted for operation on endwise 55 movement of the broach, means for applying power to the apparatus for reciprocating the broach, a collar through which said broach passes mounted to rotate on the face of said broaching machine head having 60 provision for controlling the turning of a work piece mounted on the broach, and geared connections from said broach reciprocating means for effecting timed rotation of said collar relative to the reciprocation 65 of said broach whereby a spiral path is broached in the work.

4. Apparatus of the kind described, comprising a broach provided with relatively open spiral cutting elements adapted to operate on endwise movement of the broach, means for reciprocating said broach and holding it against rotation, a collar mounted to turn and having said broach passed therethrough, said collar being equipped 75 with provision for controlling the rotation of a work-piece on said broach, and geared connections from said broach reciprocating means for effecting timed rotation of said collar relative to the broach reciprocation, 80 including a rack carried by the broach reciprocating means.

In testimony whereof, I have signed my name to this specification, in the presence of two subscribing witnesses.

RALPH R. LAPOINTE.
